CLAIM

We claim the ornamental design for a painting/palette knife, as shown and described.

DESCRIPTION

FIG. 1 is a front perspective view of a painting/palette knife, according to an embodiment of the invention;

FIG. 2 is a top view of the painting/palette knife of FIG. 1; FIG. 3 is bottom view of the painting/palette knife of FIG. 1; FIG. 4 is a side view of the painting/palette knife of FIG. 1; FIG. 5 is a rear view of the painting/palette knife of FIG. 1; and,

FIG. 6 is a front view of the painting/palette knife of FIG. 1. The broken lines showing the knife/palette tip are for environmental purposes only and forms no part of the claimed design.
